TOOL FOR HANDLING BATTERIES

Jacob Plannie Gantt, Rock Hill, S. C.

Application April 3, 1943, Serial No. 481,673

3 Claims.

(Cl. 294—99)

This invention relates to an apparatus for carrying objects such as batteries and the like from place to place. More specifically, it relates to a handle having a plurality of gripping means for engaging an article, the tenacity with which said gripping means engages the article being directly in proportion to the weight of the article being lifted, plus any gripping action which may be applied by the hand of the operator.

It is, therefore, an object of this invention to provide a device for carrying objects such as batteries and the like which has gripping means controlled by the weight of the article itself, and also can be controlled by the grip of the hand of the operator. By providing such a device, it is possible to carry heavy objects from place to place and yet rest assured that the grip which the holder has upon the object will increase rather than decrease due to the weight of the object.

It is another object of this invention to provide an article of the class described having a pair of gripping means associated therewith and a flexible connection between said gripping means whereby the distance between the same can be varied. By the provision of this feature, the holder is adaptable to batteries which have posts at variable distances apart.

It is another object of this invention to provide an improvement over my Patent No. 2,157,753 of May 9, 1939, by providing a removable gripper link between the two jaws for gripping each of the terminal posts of the battery so that the gripper link can be slid upwardly on the jaw members after they have been manually pressed together, so that they can then be seized and spread further apart from each other should they, by use, lose some of their resiliency, and be disposed too close together to engage the terminal of a particular battery. Or, the lower ends of the jaws can be pressed together and the gripper links entirely removed so the jaws can be manually spread apart.

The apparatus is especially adapted for use in removing, installing, and handling automobile, truck, and airplane batteries.

Some of the objects of the invention having been stated, other objects will appear as the description proceeds, when taken in connection with the accompanying drawing, in which:

Figure 1 is an isometric view of the invention shown associated with a battery represented in dotted lines;

Figure 2 is an elevation of one end of the invention showing the gripping means in released position;

Figure 3 is a transverse sectional view taken along the line 3—3 in Figure 1.

Referring more specifically to the drawing, the numeral 10 indicates a battery in dotted outline which is adapted to be handled by my invention. This battery has terminals 11 and 12. My invention comprises a handle member 13, which is composed of any suitable resilient or bendable material, such as rubber or rubberized or otherwise treated plies of fabric, or, in fact any suitable insulating material which has sufficient strength to support the weight of a battery. This handle member 13 has fixedly secured thereto, by means of suitable rivets 14, jaw members 15 and 16, which are turned inwardly as at 17 and 18, the sharpened points 17 and 18 being adapted to grip the terminal of a battery. The jaw member 15 instead of having a thickened portion for supporting the gripping link, as in my previous patent, has struck therefrom a lug or ear 20 which projects inwardly. Immediately below the lug 20, the jaw 15 slopes inwardly, thus providing a surface 22 on which the link 25 rests. The jaw 16 slopes downwardly to a point just short of its end to provide a cam surface extending down to the point where the gripping link engages the jaws 16 as shown in Figure 1.

The gripping links, each comprise a rectangular member 25 having a cross member 26 which is adapted to rest immediately below the lug or ear 20 and above the cam surface 22. The proximate ends of the gripping link, indicated by reference character 24 have suitable U-shaped members 27 loosely surrounding the same and the ends of a handle member 28 are secured to these U-shaped members 27 by any suitable means such as rivets 29. The outer ends of the gripping links are indicated by reference character 30. The member 28 may be composed of any suitable material, such as webbing, leather, pieces of tire casing fabric, or any suitable material. Disposed on the lower side of the member 28 is a reinforcing member 32, such as a piece of wood. This is secured to the member 28 by any suitable means such as rivets 33.

In operation, the jaws 15 and 16 normally are spread apart to a greater degree at their lower ends than the width or thickness of the terminal posts of a battery. This causes the knife edges 17 and 18 to be disposed on each side, but in spaced relation to the terminal of a battery when

the tool is placed over the battery as shown in Figure 1. With the palm of the operator's hand resting on top of the handle member 13, the fingers of the operator's hand engage the member 32, and by gripping the handle 13 and the member 32 and causing the member 32 to move upwardly towards the handle 13, the cam action by the riding of the portion 30 of the gripping link on the outer surface of the jaws 16, causes the knife edges 17 and 18 to be moved towards each other to grip the terminal of the battery, as shown in Figure 1. With the battery thus gripped, the operator lifts the battery, and all of the weight of the battery rests on the strip 28. When the battery is desired to be released, it is placed on a suitable support, and thus the pressure is released on the jaws 15 and 16, and the edges 17 and 18, due to their inherent resiliency, move apart from each other to the position shown in Figure 2. Thus, the two can be immediately separated from the battery; in other words, it is automatically separated from the battery when the battery ceases to be supported by the tool.

One big advantage of the present tool over that shown in my above-mentioned patent, is that if it is desired to spread the jaws 15 and 16 apart from each other at their lower ends, they can first be pressed towards each other until the cross portion 26 of the gripping link will ride above the ear 20 upwardly onto the jaws to where they are closer together, and then the lower ends of the jaws 15 and 16 can be seized and spread apart from each other, and then the gripping link can be moved downwardly to a position beneath the ear 20, and thus by springing the jaws apart from each other, they will regain their inherent resiliency to stay the desired distance apart at their lower ends. Or, the same result can be obtained, by squeezing the ends of the jaws 15 and 16 together and removing the gripping links entirely from the jaws.

In the drawing and specification, there has been set forth a preferred embodiment of the invention and although specific terms are employed, they are used in a generic and descriptive sense only, and not for the purpose of limitation, the scope of the invention being defined in the claims.

I claim:

1. A carrier for batteries having two spaced

terminals comprising a pair of members for engaging each terminal, a common bridge member to which the ends of the pairs of members are secured, a lug projecting from one of each pair of members, a rectangular link having a cross member loosely and removably confined below the lug, one end of each link slidably contacting the outer surface of the other of the pair of members, a strap having its ends secured to the other end of each of said links and being engageable by the hand of an operator in the act of lifting the battery to press said members together to grip the terminals of the battery.

2. A battery tool for handling batteries equipped with a pair of terminals, a resilient member, a pair of prongs secured to each end of the resilient member and engaging the terminals of a battery, one of the prongs being resilient and having a tendency to move away from the terminal with which it is associated, a lug projecting from one of each pair of members, a rectangular link having a cross member loosely and removably confined below the lug, one end of each link slidably contacting the outer surface of the other of the pair of members, a strap having its ends secured to the other end of each of said links, whereby when upward pull is exerted on the strap, the prongs will be pressed toward each other to grip the terminals, and the weight of the battery will cause said prongs to continue to engage said terminals until the battery has been placed in a state of rest.

3. A battery lifter comprising a resilient and bendable member, a pair of prongs secured to each end of the resilient member, the lower ends of said prongs being adapted to be placed on each side of the terminal of a battery, a link removably secured on one of the prongs and slidably engaging the other prong, said links being slidable upwardly on the prongs or removable from the prongs when the prongs are manually pressed towards each other, a strap connecting the proximate ends of the links, said strap being adapted to be engaged by the hand of the operator to exert upward pull of the strap to thereby cause the prongs to grip the terminals sufficiently to lift the battery as the upward pull of the hand of the operator is increased.

JACOB PLANNIE GANTT.
